US00D729115S

(12) **United States Design Patent**
Prinster et al.

(10) **Patent No.:** **US D729,115 S**
(45) **Date of Patent:** **** May 12, 2015**

(54) **INDOOR GROWING UNIT**

(71) Applicant: **OMS Investments, Inc.**, Los Angeles, CA (US)

(72) Inventors: **Mark Gerard Prinster**, Marysville, OH (US); **Bradley Alan Schultz**, Powell, OH (US); **Kimberly Ann Rygielski**, Powell, OH (US); **Matthew L. Phillips**, Litchfield, CT (US); **Robert H. Bruno**, Avon, CT (US); **Tara Marie Zasadzinski**, Marysville, OH (US)

(73) Assignee: **OMS Investments, Inc.**, Los Angeles, CA (US)

(**) Term: **14 Years**

(21) Appl. No.: **29/445,794**

(22) Filed: **Feb. 15, 2013**

(51) LOC (10) Cl. **11-02**

(52) U.S. Cl.

USPC **D11/144**

(57) **CLAIM**

We claim the ornamental design for an indoor growing unit, as shown and described.

DESCRIPTION

FIG. 1 is a perspective view of an indoor growing unit.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a rear perspective view thereof.

FIG. 9 is a perspective view of thereof in a condition of use; and,

FIG. 10 is an exploded parts view of the components thereof. The broken lines in the drawings illustrate environmental structure on the article and form no part of the claimed design.

1 Claim, 10 Drawing Sheets
